UNITED STATES PATENT OFFICE

SYLVESTER A. JOHNSON, OF NORTH PROVIDENCE, RHODE ISLAND, ASSIGNOR TO
ALBERT E. R. SPEIDEL, OF EDGEWOOD, RHODE ISLAND

CLASP FOR BRACELET STRAPS

Application filed May 23, 1931. Serial No. 539,497.

This invention relates to an end member for a bracelet strap, particularly a cord bracelet or the like; and has for its object to provide a construction by which the strap 5 may be easily positioned into one portion of the clasp and then the other portion moved into binding engagement therewith.

Another object of the invention is the provision of means whereby one jaw member 10 may be bodily removed from the other jaw of the clasp and then suitably moved into binding engagement with the strap.

Another object of the invention is the provision of means whereby the end member 15 may be clasped to a strap or the like in a manner quicker than that provided where the ends are threaded into the end member.

A further object of the invention is the provision of an end member which will be 20 smooth on the surface contacting with the arm to prevent abrasion or catching of the device in the sheer fabric of the clothing of the wearer.

A still further object of the invention is 25 the provision of a construction by which the movement of the gripping member into gripping position will continue to tighten its binding engagement upon the strap throughout its movement rather than passing a peak 30 of binding engagement and then diminishing.

With these and other objects and advantageous features in view, the invention consists of a novel arrangement of parts more 35 fully disclosed in the detailed description following, in conjunction with the accompanying drawings, and more particularly set forth in the appended claims.

Fig. 1 is a top plan view of the cord 40 bracelet with my improved end member secured thereto.

Fig. 2 is an enlarged view of the top surface of the end member.

Fig. 3 is a side elevation thereof.

Fig. 4 is a bottom plan view of the end member with a cord or strap bracelet attached thereto.

Fig. 5 is a view similar to Fig. 4 showing the strap removed and the clasp in open position.

Fig. 6 is a section view showing the clasp in open position.

Fig. 7 is a view similar to Fig. 6 with the clasp partly moved to closed position.

Fig. 8 is a view similar to Figs. 6 and 7 55 with the clasp moved to closed position.

Fig. 9 is a sectional view on the line 9—9 of Fig. 8.

In the use of strap bracelets which are made of fabric or material which easily 60 frays, it is found difficult to thread such a strap, particularly cords of silk or the like, beneath a clamping member which is pivoted to the side walls of the body of the clasp and consequently a large amount of time is 65 consumed in assembling such a cord and end member, and in order to simplify the assembly operation, I have provided a construction by which one of the jaws or the gripping member of the clasp may be completely removed from the body member or other jaw 70 to allow the cord to be laid in as distinguished from threading beneath the end member, after which the gripping member is moved to position its end beneath suitable 75 lugs or projections and then swung to cause the gripping member to act against these lugs or projections and move toward the body member and into firm engagement with the cord or strap; and the following is a detailed 80 description of the present embodiment of this invention illustrating the improved means by which these advantageous results may be accomplished:

With reference to the drawings, 10 designates the body member of the clasp which is provided with a top wall 11, and side walls 12 forming a generally channel shaped construction. Projections 13 extend inwardly from the side walls at one end and a gripping member 14 is movably attached to the body by means of a link 15 which is provided with trunnions 16 at one end pivoted in the side walls 12 at the opposite end and which link is provided with trunnions at its opposite end 90 to be pivoted in the ears 17 of the gripper 14. This gripper 14 is provided with a toothed flange 18 and is offset as at 19 providing a cam surface 20.

In operation the gripper is lifted from the 100

body as shown in Fig. 7 permitting free access to the body to lay the cord 21 therein after which the gripper is positioned as shown in Fig. 7, with the cord 21 between the side walls 12 and with the cam surface 20 extending beneath the projections 13. The same is then swung about its pivot to the link 15 with a sliding action along the projections 13 to move the toothed flange 18 beneath these projections to the position illustrated in Fig. 8 and thereby swinging the connecting link 15 as illustrated in Fig. 8. The offset 18 therein permits the outer surface 22 of the gripper to lie flush with the projections 13 and also forms a space for the reception of the link 15 for compact arrangement of the parts.

The major portion of the gripper is domed or convexed on its outer surface to provide a smooth surface for the wrist and also forms a convenient curve to remove all sharp edges and prevent the end member from catching in the sheer clothing of the wearer.

The body of the clasp may be provided with any suitable attaching connection. I have here illustrated a hook 23 for engagement with the frame shaped link 24 to receive the center connector 25 by which the bracelet may be detached one part from the other for removing a wrist watch or the like from the wrist. The body member is also provided with a rib 25 to assist in positioning the cord bracelet or the like therein and which also serves to stiffen and strengthen the body member of the clasp.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. An end clasp for a strap or the like, comprising a body member having upstanding portions along its sides, a gripper member, a link connecting said members together, and cooperating means between said members for binding a strap or the like between them, including a laterally-extending overhanging portion from one of said upstanding portions on said body member beneath which said gripper may extend.

2. An end clasp for a strap or the like, comprising a body member having upstanding portions along its sides, a gripper member, a link pivoted to each of said members and connecting them together, and means whereby said members may be manipulated to clamp a strap between them, including a laterally extending overhanging portion from one of said upstanding portions on said body member beneath which said gripper may extend.

3. An end clasp for a strap or the like comprising a body member, a gripper mem-

ber, a link connecting said members together and cooperating means between said members for binding a strap or the like between them comprising projections on one of said members and a cam surface on the other of said members for engagement with said projections to force the gripper member toward the body member.

4. An end clasp for a strap or the like comprising a body member, a gripper member, a link connecting said members together and cooperating means between said members for binding a strap or the like between them including projections extending inwardly from the opposite sides of said body member beneath which one end of the gripper member may be placed and swung to closed position.

5. An end clasp for a strap or the like comprising a body member, a gripper member, a link connecting said members together and cooperating means between said members for binding a strap or the like between them, comprising inwardly extending projections on said body member beneath which is positioned one end portion of the gripper member and a cam surface on said gripper member to engage said projections and force said gripper into engagement with the strap upon being swung to closed position.

6. An end clasp for a strap or the like comprising a body member having a bottom wall, projections spaced from said bottom wall, a gripper member having teeth at one end, said end being insertable beneath said projections, a link pivoted to the gripper member at a point spaced from said end and connected at its opposite end to said body member whereby when said gripper is swung on said link connection with its end under said projections, said end moves toward said bottom wall to bind a strap or the like between said members.

7. An end clasp for a strap or the like comprising a body member having a bottom wall, projections spaced from said bottom wall, a gripper member having teeth at one end, said toothed end being insertable beneath said projections, a link pivoted to the gripper member at a point spaced from said end and connected at its opposite end to said body member whereby when said gripper is swung on said link connection with its end under said projection, said end moves toward said bottom wall to bind a strap or the like between said members, the portion of said gripper located beneath said projections being offset from the remainder thereof whereby to cause the major portion of said gripper to lie in the plane of said projections.

8. An end clasp for a cord bracelet comprising a body member having side walls, projections extending inwardly from the side walls at one end thereof, a gripping member having teeth at one end and a cam sur-

face adjacent said end, a link pivoted at one end to the opposite end of the side walls and at its opposite end to said gripper member whereby said gripper member may be lifted 5 from the body member for the reception of a cord bracelet end or the like and then closed by moving the end with the cam surface beneath said projections and swinging the member downwardly to cause the teeth at said 10 end to bind the bracelet between said members.

In testimony whereof I affix my signature.
SYLVESTER A. JOHNSON.
